UNITED STATES PATENT OFFICE.

AUGUSTUS F. HARTER, OF CHICAGO, ILLINOIS, ASSIGNOR TO CRIBBEN & SEXTON COMPANY, OF CHICAGO, ILLINOIS, A CORPORATION OF ILLINOIS.

DESIGN FOR A BASE-BURNER.

● 45,631.

Specification for Design.

Patented Apr. 21, 1914.

Application filed February 12, 1914. Serial No. 818,415. Term of patent 7 years.

To all whom it may concern:

Be it known that I, AUGUSTUS F. HARTER, a citizen of the United States, residing at Chicago, in the county of Cook and State of Illinois, have invented a new, original, and ornamental Design for Base-Burners, of which the following is a specification, reference being had to the accompanying drawing, forming part thereof.

The figure is a perspective view of a base burner showing my new design.

I claim:

The ornamental design for a base burner as shown.

AUGUSTUS F. HARTER.

Witnesses:

W.M. F. FREUDENREICH,
RUTH E. ZETTERVALL.
